No. 37,022.

Patented July 5, 1904.

UNITED STATES PATENT OFFICE.

LUCILE WEBB BANKS, OF COLUMBUS, MISSISSIPPI.

DESIGN FOR A HANDLE FOR SPOONS, FORKS, OR SIMILAR ARTICLES.

SPECIFICATION forming part of Design No. 37,022, dated July 5, 1904.

Application filed May 21, 1903. Serial No. 158,210. Term of patent 3½ years.

To all whom it may concern:

Be it known that I, LUCILE WEBB BANKS, a citizen of the United States, residing at Columbus, in the county of Lowndes and State of Mississippi, have invented a new, original, and ornamental Design for the Handle of a Spoon, Fork, or Similar Article, of which the following is a specification, reference being had to the accompanying drawing, forming a part thereof.

The accompanying drawing is a plan view of a spoon.

What I claim as new, and desire to secure by Letters Patent, is—

The ornamental design for the handle of a spoon, fork, or similar article, as shown.

LUCILE WEBB BANKS.
